UNITED STATES PATENT OFFICE.

ANDREW J. REAMS, OF CHICAGO, ILLINOIS, ASSIGNOR TO SYLVO REAMS,
OF SAME PLACE.

PROGRAM-CLOCK.

SPECIFICATION forming part of Letters Patent No. 660,312, dated October 23, 1900.

Application filed March 1, 1897. Serial No. 625,594. (No model.)

To all whom it may concern:

Be it known that I, ANDREW J. REAMS, a citizen of the United States, residing at Chicago, in the county of Cook and State of Illinois, have invented certain new and useful Improvements in Automatic Program-Clocks, of which the following is a specification.

The object of my invention is to provide a simple, economical, and efficient automatic annunciator system; and the invention consists in the features, combinations, and details of construction hereinafter described and claimed.

In the accompanying drawings, Figure 1 is a front elevation of one of my annunciators; Fig. 2, an enlarged sectional detail taken on line 2 of Fig. 1 looking in the direction of the arrow. Figs 3 and 4 are transverse sections taken on lines 3 and 4, respectively, of Fig. 2; Fig. 5, a bottom plan view of a portion of the guide-ring, hereinafter described; Fig. 6, a rear elevation of the mechanism for operating the annunciators with the back frame removed; Fig. 7, a sectional view taken on line 7 of Fig. 6; Fig. 8, a sectional view taken on line 8 of Fig. 7; Fig. 9, a front elevation of the regulator and motor inclosing case; Fig. 10, a sectional detail elevation showing a part of the releasing mechanism arranged to be operated by the regulator and located within the regulator-frame, taken on line 10 of Fig. 11; Fig. 11, a cross-sectional elevation taken on line 11 of Fig. 9; Fig. 12, a detail front elevation of the mechanical cut-out located at the bottom of the regulator-clock shown in Fig. 9 with the daily dial removed; Fig. 13, a similar view with the index-plate removed; Fig. 14, a rear elevation of the mechanism shown in Fig. 12 with the bearing-plate shown in dotted lines; Fig. 15, a plan sectional view taken on line 15 of Fig. 12; Fig. 16, a front elevation of the motor for making and breaking the annunciator-circuits with its inclosing case removed; Fig. 17, a detail elevation of a portion of the motor mechanism, illustrating it as it may be used in connection with an electromagnet; Fig. 18, a rear elevation of the battery-switch shown at the bottom of Fig. 16, and Fig. 19 a diagrammatic view showing the arrangement of circuits.

This invention relates to that system of mechanism which is used in schools, colleges, and similar institutions for the purpose of announcing at certain predetermined times 55 that certain recitations must be changed or take place and in which several annunciators are operated or their movements controlled from one central source of motive power, generally a clock of the type known 60 as "regulators."

The principal object of my invention is to provide a system of this kind which shall be largely, if not entirely, controlled and the mechanisms released by the use of electro- 65 actuated mechanism, principally magnets, such magnets being energized at predetermined periods of time, due to the closing of the circuit, by mechanism controlled by a central or main regulator. 70

In providing mechanism for my system I use a regulator-clock which is provided with a cut-out having means for opening and closing a main circuit at any time or times during the one hundred and sixty-eight hours 75 that constitute a calendar week. This regulator is provided with a motor the operations of which are permitted or stopped at predetermined times, so as to energize the annunciator circuit or circuits at certain periods of 80 time, preferably every five minutes, and thereby operate or permit the operation of the annunciators. I further provide an annunciator or several annunciators electrically connected with the source of electric energy 85 and with the make-and-break mechanism of the motor, such annunciators having adjustable contact-points by which the local circuit is closed and a signal sounded at any desired time or times, and, finally, I provide switch 90 mechanism on the motor by which a set of batteries may be used in multiple relation with each other, so that one battery or set of batteries is used for a predetermined period of time and allowed to rest a predetermined 95 length of time, thereby prolonging the life and efficiency of such batteries. These mechanisms are constructed and arranged to operate in combination and perform the result desired in the manner hereinafter described. 95

In illustrating and describing my improvements I will only illustrate and describe the

mechanism which I consider to be new and essential for the purpose of disclosing my invention to enable those skilled in the art to practice the same, leaving out of consideration old and well-known mechanisms, which would only tend to confuse and render ambiguous the novel features. I will say, further, that I will show and describe my mechanism in what I consider the preferred form, but do not desire to be limited to this form, as it will be evident to those skilled in the art that the details of arrangement and form may be varied without departing from the spirit of the invention.

15 I will first describe the regulator to be used in my system, (see Fig. 9,) but will not show or describe its ordinary time-keeping train, which is well known in the art. As is well known, schools are open but five days in the 20 week, being closed for Saturday and Sunday, and, generally speaking, there are no sessions of school during the evenings. In order, therefore, to permit the mechanism to be used only at the desired times either day or night, 25 I provide a regulator with means by which the main circuit is opened and closed at these times and the motor for operating the switch permitted to be operated or prevented from operating at other times. In order to provide 30 mechanism of this kind, I use a dial A, which is secured by any desired means to the frame A' of the regulator. This dial, which contains the names of the seven days of the week, is mounted upon a rotatable shaft a and provided with fourteen pin-holes, each pin-hole representing twelve hours. If it be desired 35 to close the electric circuit on any of these days and, as shown in the drawings, for the daytime of Monday, Tuesday, Wednesday, Thursday, and Friday, the pins a' are inserted 40 in the pin-holes a² of said dial. Arranged on the ring A² and insulated therefrom are two spring contact-points a³ and a⁴. These spring-contacts are connected by means of the wires 45 a⁵ and a⁶ with the main circuit, which includes an annunciator, the make-and-break mechanism, and source of electric energy, and as the week-dial rotates a pin a' will strike the contact-spring a⁴ and raise the same so 50 as to bring it into electric contact with the other spring-contact, (see Fig. 9,) and thus close the main circuit. As shown in Fig. 9, when the dial is rotated, so that the pin is removed from operating the spring-contact, such 55 contact a⁴ will drop and the main circuit be broken, thereby preventing the operation of the parts or the conveying of current to the annunciators.

In order to prevent the operation of the 60 motor, which motor will be hereinafter described, I pivot a stop-lever having two arms A³ and A⁴ to the ring A² at a' (see Fig. 9) and provide one of these arms with a block a⁸, arranged to be contacted by one of the pins a'. 65 As shown in Fig. 17, the motor is provided with a fan against which the arm A³ on the stop-lever may impinge to prevent it from ro-

tating. When the parts are in the position shown in Figs. 9 and 17, the stop-lever is removed from the path of rotation of the fan, 70 so that if all other means are free such motor can operate at the desired times. As the pins on the week-dial pass out of contact with one arm of the stop-lever the upper end will drop and the lower portion be moved over by means 75 of the spring a⁹, so as to contact the fan of the motor and prevent its operation until the next pin on the week-dial raises and removes such stop-lever from contact with the fan of the motor.

In order to rotate the week-dial in a step-by-step manner and at the desired times, I provide the shaft upon which it is mounted with a notched wheel B, having any desired number of notches. As shown in the drawings, (see Figs. 12 and 14,) it has fourteen notches corresponding to the number of pins in the week-dial—one for every twelve hours of the week—thus providing for the movement of the week-dial once every twelve hours. 80 This same shaft is provided with an independently-mounted compound lever b, arranged in the path of an arm B', which is connected with the hour-wheel of the regulator to rotate with the same, and during every 85 twelve hours, or one complete rotation of the hour-hand, it will contact the compound lever and move it to its limit in one direction and then release it, so that a coiled spring b' may restore it to its normal position, as 90 shown in Fig. 14. The lever is preferably made compound or in two parts b and b², as shown particularly in Figs. 13 and 14, so that they have a very slight independent lateral movement for the purpose of operating the 95 mechanism more efficiently. The lower lever is provided with a dog b³, arranged to engage with the notches or indices b⁴ on the notched wheel, and the ring-frame of the 100 week-day dial mechanism is provided with a pawl B⁵, arranged to engage the indices at 105 determined times to position the dial. As the lever-arm is moved forward or in the direction indicated by the arrow in Fig. 14 the dog on the compound lever rides out of the 110 notch with which it is in engagement by having its beveled front end contact the walls of the notch and force it out. The continued movement of the compound lever brings the 115 hooked free end of the dog into engagement with the next notch, and as the arm on the 120 regulator-clock releases the compound lever the coiled spring b' restores such lever to its 125 normal position and brings the pin b⁵ on the upper lever into engagement with the lower lever, as shown in Figs. 13 and 14, so as to 130 permit the trip B⁴ to strike the pawl and remove it from engagement with the notched wheel and permit the dog b³ to rotate the notched wheel one step in its rotation and bring the next pin or hole opposite the stop-levers and spring-contacts on the main circuit, so that if there be a pin in such hole such circuit will be closed and the stop mech-

anism operated so as to liberate the switch-motor.

It is well known that less battery-power is required to operate electromechanism when it is operated successively than would be required to operate an aggregation of such mechanisms simultaneously. For instance, I may desire to arrange twenty-five annunciators in a school-building and place them on five circuits, with five annunciators on each circuit. If I operate these twenty-five annunciators simultaneously or during the same period of time, it would require a comparatively-large amount of electric energy, and as these annunciators should only be operated or moved every five minutes the energy used would be disproportionate to the work performed. I therefore desire to provide mechanism to energize these circuits successively, but during such a short period of time that to all intents or for practical purposes it is simultaneous. In order to accomplish this result, I provide what I term a "switch-motor," (shown particularly in Figs. 16, 17, and 18,) in which there is a frame C, having a train of wheels adapted to drive and rotate what I term a "rotating contact-shaft" c. This train consists of two shafts c' c², having power-springs c³ thereon, and is provided with driving-wheels C' and C², which mesh with a pinion (not shown) on a shaft c⁴, such shaft bearing a wheel c⁵, that engages with a pinion (not shown) on its rotating contact-shaft. This contact-shaft is provided with a two-armed contact-piece C³, arranged during its rotations to successively contact the spring contacts or terminals c⁶, c⁷, c⁸, c⁹, and c¹⁰ and energize the main circuits that lead therefrom by means of the wires c¹¹, c¹², c¹³, c¹⁴, and c¹⁵. For convenience in giving signals or sounding the annunciator it is desirable to energize these currents every five minutes. In order to accomplish this result by mechanical means and stop the mechanism at all other times, I provide a let-off, which is constructed and operated as follows: The contact-shaft is provided with a wheel C⁴, which also engages and operates a fly or fan C⁷ by means of the pinion and shaft C⁸. The contact-shaft c is provided with a notched disk C⁹ and is prevented from rotating by means of the vibrating of a movable stop C¹⁰, which is pivotally mounted in a shaft C¹¹. A second hooked stop C¹² is pivoted in the same shaft and has its outer free end arranged to hold the fly or fan from rotating, and consequently prevent the motor from operating. In order to release the parts at predetermined times, I provide the main arbor D of the regulator with a pin-wheel d, bearing twelve pins d'—one for every five minutes—arranged to operate against the free end of a vibrating releasing-lever D'. This releasing-lever is provided with a connecting-rod d², that connects with the stops C¹⁰ and C¹² to operate and raise the same, so as to release the notched disk C⁹ and the fan or fly C⁷, and thus enable the

motor to operate. As the pin-wheel is on the shaft that rotates the minute-hand once in an hour and is provided with twelve pins, it will be seen that the motor is released once every five minutes and the contact-shaft allowed to make its desired rotation, so that one of its contact-arms successively closes, and consequently energizes, the five circuits above named. As the pins d' pass out of contact with the releasing-lever D' the lever resumes its normal position, owing to the weight of the other parts, and stops the motor after the rotating contact-shaft c has made half of a revolution. In order to prevent the rotation of the contact-shaft through a greater period of time and longer than is necessary, I provide a third stop d³ and the wheel C⁵ with a pin d⁴. It will be seen that the connecting-rod of the releasing-lever raises this third stop into the path of the pin d⁴ and prevents the complete operation of the motor until the releasing-lever has resumed its normal position. At the same time it will be seen that it may make a partial operation, so that the stop C¹⁰ is removed from alignment with the notch in the notched disk C⁹. It will thus be seen that there are three means of stopping the motor and making and breaking the mechanisms from operating—first, the week-disk, with its pin-holes and pins, which are arranged to actuate the stop-lever A⁸ and prevent the fan C⁷ from operating; second, the vibrating stop-lever d³, which is arranged to contact the pin d⁴ on the wheel C⁵, and, third, the hook-stop C¹², which is also arranged to engage the fan C⁷ and be disengaged at desired times.

The batteries or sets of batteries are electrically connected with the frame of the motor, as shown in Fig. 18, by means of the wires E, E', and E², which lead to three sets of batteries. Each wire has a spring-terminal which bears on a contact-collar E³ of a rotating shaft e. This contact-collar is provided with an insulating portion e', and, as shown in Fig. 18, but one terminal or brush can be electrically connected with such collar at a time, so that but one battery or set of batteries is in position to be used. In order to rotate this shaft and consequently switch the electric connection from one set of batteries to the other at predetermined periods of time, I provide such shaft with an index-plate E⁴, having any desired number of notches. The shaft is further provided with a compound vibrating lever E⁵, arranged to be contacted by a pin on the wheel c⁵. The lever is also provided with a dog e² and the frame with a pawl e³. Such compound lever is further provided with a trip e⁴, all constructed in exactly the same manner as the mechanism described in Fig. 14. A coil-spring e⁵ is used to restore the lever to its normal position. The arrangement of the parts is such that during the rotation of the motor-wheel c⁵ the lever is moved over and its dog rides out of engagement with the in-

dex-plate, so that the moment such lever is released the coil-spring operates to throw it back, and the trip e^4 , moving the pawl out of engagement with the index-plate, permits the movement of such lever to rotate the shaft, with its contact-collar, one step in its rotation. The timing of the parts is such that each one of the battery-terminals is electrically connected with the contact-collar for a period of 10 two hours and is out of contact with such part and at rest for a period of four hours. In other words, it takes six hours for the contact-collar to make a complete rotation, and as each battery or set of batteries are in contact for two hours out of the six they have four hours' rest and time for restoration. This is a decided advantage in that it allows the use of primary batteries in an economical and efficient manner.

20 It may be found desirable to dispense with the mechanical stop mechanism and provide electromechanical mechanism. In order to accomplish this result, I provide the motor with an electromagnet F, as shown in Fig. 17, 25 and one of the rotating shafts d^{10} with an armature f, arranged over the pole or poles of the magnet. Instead of having a release-lever (see Fig. 10) the pins may be arranged to bear against the brush f' , which is insulated 30 from the frame of the clock and provided with a wire f^2 , that leads to a battery, and the frame with a wire f^3 , that leads to a corresponding wire f^3 and the magnet, while the wire f^2 corresponds with the wire f^2 in Fig. 35 10 and also leads to the battery. It will thus be seen that the magnet will be energized every five minutes and the stop and release mechanism operated every five minutes exactly in the same manner as the mechanical 40 release mechanism.

Having described the regulator and the means by which I make and break the annunciator and main circuits, I will proceed to describe the annunciator.

45 In Fig. 1 of the drawings I have shown a front elevation of the annunciator, which is provided with a dial having the usual hour-markings and an outer ring bearing markings for every five-minute movement of the 50 hour-hand, making one hundred and forty-four in all, or twelve between each hour. I provide a corresponding number of sliding contact-pieces G at a point inside of the hour-markings, which are confined and held in place by means of a holding-ring G', which 55 may be secured to the dial by means of screws g, as shown in the drawings, or in any other desired manner, and is slotted, as at g', so that the sliding contacts may be held in the 60 desired position. These sliding contacts are connected with one terminal or pole of a local or supplemental circuit and the hour hand or shaft with a second pole of the local circuit, which includes a battery and a bell. 65 The hour-hand G² is provided with a brush g², which is arranged underneath the same,

so that it may contact the sliding or adjustable contacts whenever they are drawn out, and thus close the local circuit at the desired time or times, as shown in Figs. 1, 2, and 3. 70 It will thus be seen that, if desired, the annunciator will close a local circuit, give a signal, or sound an alarm during any five minutes of each of the twelve hours.

To operate the pointers or hands on the annunciator at the desired times, I provide a train of wheels and pinions $g^3, g^4, g^5, g^6, g^7, g^8$, and g^9 and a fly or fan shaft and pinion g^{10} , the initial or driving shaft being provided with a power-spring G³. The shaft upon 80 which the wheel and pinion g^6 and g^7 is mounted is provided with a notched disk g^{11} , having but two notches and which is arranged to be engaged by a vibrating stop g^{12} , which is pivotally mounted on a rock-shaft g^{13} . The 85 same shaft bears a limiting-stop g^{14} , which prevents the parts from rotating but a portion of their distance until the magnet which operates the same has been deenergized, as hereinafter described. To release the stop 90 mechanism from engaging with the notched disk, I provide an electromagnet H, which is electrically connected with a source of electric energy and with one of the battery-terminals by means of the wires h or h', so that 95 when the rotating contact of the motor electrically closes a circuit such magnet is energized, the armature h² pulled down, and by means of the rod h³, that extends therefrom, the stop g^{12} raised out of engagement with 100 the detent-disk and its limiting-stop g^{14} raised into position to stop the pin g^{16} , but permitting the detent-disk to make a very short 105 part of its rotation. As soon as the magnet is deenergized the springs g^{17} restore the parts 110 to their normal position and permit the train to be operated until the detent-disk, with one of its notches, comes into line again with the stop. As the regulator energizes these 115 operations will occur every five minutes and the hands or pointers on the annunciator be moved a five-minute step each time, or one-twelfth of its rotation, so that the local circuit, as hereinafter described, may be closed 120 every five minutes and a signal or alarm given.

It may also be desirable to set the hands of the annunciator without interfering with the other mechanism. In order to accomplish 125 this, I provide a central shaft I, which carries the minute hand or pointer H'. Mounted upon the bearing for this shaft is a sleeve i, that carries a ratchet-wheel i' and which has an independent movement from the wheel i², which is driven in any suitable manner so as 130 to provide the relative rotation between the hour and the minute hands. This wheel, which we will call the "hour-wheel," in that it controls the movement of the hour-hand, is provided with an arm i³, which carries a click or dog i⁴, engaging with the ratchet-wheel.

As the hour-hand is mounted tightly upon the sleeve *i* of the ratchet-wheel, it will be seen that it may be moved forward independent of the hour-wheel, but is prevented from 5 being moved backward. At the same time the rotation of the hour-wheel is positively transmitted to the hour-hand by means of the arm, dog, and ratchet-wheel above described. The minute-shaft is independently mounted 10 and provided with the usual frictional springs for transmitting power between it and the other portion of the train, which, however, is well understood by those skilled in the art.

In Fig. 19 I have shown a diagrammatic 15 view of my combined mechanism, in which *c* is the rotating contact-shaft that makes and breaks the annunciator-circuits; *C*³, the rotating contact-collar for the battery-switch; *A*, the week-dial with its pins; *H*, the annunciator-magnet; 4, the contact-wheel on the annunciator; 5, the brush of the contact-wheel 4; 6, the signal-bell; *G*², the hour-hand; *G*, the sliding contact of the annunciator-dial, and 1, 2, and 3 the batteries. When the main 20 circuit is closed and the motor has been started, the rotating contact-shaft in the position shown in Fig. 19 will first strike the brush *c*¹⁰, so that the electric current will flow from battery 2 through the wire *E*' and its 25 terminal to the rotating contact-collar *E*³, wire *k*, leading to the rotating contact-shaft *c*, brush *c*¹⁰, wire *c*¹⁵, and wire *h* to magnet *H*, energizing the magnet. The electric current will then pass through the magnet and re- 30 turn by the wire *h*' and wire *a*⁶, spring-terminals *a*⁴ and *a*⁵, and wire *a*⁵ to battery 2. The magnet *H* of the annunciator being energized as above described draws down the pivoted armature-lever *h*² and raises the arm 35 40 or rod *h*³, throwing the tops *g*¹² out of engagement with the notched disk *g*¹¹, permitting the notched disk to rotate in the direction indicated by the arrow on Fig. 19, so that the rotating disk 4 comes in contact with the brush 45 50 55 and closes the local circuit for the current from the battery 7 to flow through the bell 6 and sound the alarm, and from the bell the current flows through wire 8, hour-hand *G*², brush *g*², sliding contact *g*, wire 9, rotating disk 4, brush *g*¹, and wire 10 back to the battery. The continued rotation of the parts 4 and *g*¹¹ brings them into the relative position shown in the diagrammatic view of Fig. 19, and when so returned the local circuit is broken and the parts held from further rotation and in the relation shown in Fig. 19.

While I have described my invention with more or less minuteness as regards details and as being embodied in certain precise 60 forms, I do not desire to be limited thereto unduly or any more than is pointed out in the claims. On the contrary, I contemplate all proper changes in form, construction, and arrangement, the omission of immaterial elements, and the substitution of equivalents as circumstances may suggest or necessity render expedient.

I claim—

1. In an automatic program-clock system, the combination of a regulator, a motor for operating a rotating circuit maker and breaker, a rotating dial or plate bearing devices to represent the days of the week arranged to be operated in a step-by-step manner by the movements of the regulator, a main electric circuit embracing an annunciator a source of electric energy and a pair of contacts arranged to be opened and closed by the movements of said dial-plate, and means interposed between the dial-plate and arranged to be operated thereby and the motor for holding positively such motor against operation and permitting it to be operated at desired times, substantially as described. 70 75 80

2. In an automatic program-clock system, the combination of a regulator, a motor for operating a rotating circuit maker and breaker, a rotating dial or plate bearing devices to represent the days of the week arranged to be operated in a step-by-step manner by the 90 movements of the regulator, a main electric circuit embracing an annunciator a source of electric energy and a pair of contacts arranged to be opened and closed by the movements of said dial-plate, means interposed 95 between the dial-plate and the motor for holding such motor against operation and permitting it to be operated at desired times, and supplementary means interposed between the regulator and the motor to permit 100 such motor to operate at predetermined periods of time, substantially as described. 105

3. In an automatic program-clock system, the combination of a regulator, a motor for operating a rotating circuit maker and breaker, a rotating dial or plate bearing devices to represent the days of the week or fractions thereof arranged to be operated in a step-by-step manner by the movements of the regulator, a main electric circuit embracing a pair 110 of contacts arranged to be opened and closed by the movements of said dial-plate and an annunciator or annunciators and two or more sources of electric energy, contact mechanism operated by the motor for switching the 115 batteries into and out of the main circuit successively, means interposed between the rotating dial-plate and the motor to permit and prevent the operation of the motor when desired, and means arranged to be operated by 120 the regulator to permit the motor to operate at predetermined periods of time, substantially as described. 125

4. In an automatic program-clock, the combination of a regulator, a rotatable shaft, a dial on the shaft, spaced to designate periods of time, a series of pin-holes dividing the spaces of the disk or dial into short periods of time, a series of pins for the pin-holes for the insertion of a pin in a predetermined hole 130 of the dial, a stationary ring on the frame back of the spaced disk or dial, a stop-lever pivoted to the ring and having two arms, a plug on one of the lever-arms arranged to be

contacted by the pins on the dial in its rotation, a fan normally engaged by the other arm of the stop-lever and a motor controlled by the fan, for the motor at predetermined periods of time to make and break an electric circuit, substantially as described.

5. In an automatic program-clock, the combination of a regulator, a rotatable shaft, a dial on the shaft spaced to designate periods of time, a series of pin-holes dividing the spaces of the dial into shorter periods of time, a series of pins for the pin-holes for the insertion of a pin in a hole of the dial for a predetermined period of time, a stationary support on the frame back of the spaced dial, a stop-lever pivoted on the support and having two arms, a block on one arm of the lever arranged to be contacted by the pins of the dial as the dial is rotated, a fly or fan normally engaged by the other arm of the lever, said lever moved out of engagement by contact of the block with a pin, a spring returning the arm of the lever to normally engage the fly or fan and a motor controlled by the fly or fan, for the motor at predetermined periods of time governed by the pins of the disk to make and break an electric circuit, substantially as described.

6. In an automatic program-clock system, the combination of an annunciator provided with characters to denote periods of time, hour and minute pointers on such annunciator to indicate the periods of time—the hour-hand being connected with a source of electric energy, radially-movable contact-pieces mounted on the dial of the annunciator and corresponding to the divisions of time thereon and adapted to be moved in or out to close contact with the hour-hand and thereby close a local circuit, a ring provided with radial slots for holding the movable contacts in position, a contact-point on the hour-hand arranged to contact the movable contacts when brought into the desired position, a local circuit embracing a source of electric energy, a signal connected to the hour-hand and movable contacts so that when the circuit is closed by the contact on the hour-hand contacting one of the movable contacts the signal is operated, a motor in the annunciator for operating the hand mechanism, and means for releasing the motor of the annunciator at predetermined periods of time, substantially as described.

55. 7. In an automatic program-clock, the combination of a regulator, a rotatable shaft, a dial on the shaft spaced to designate days of the week, a series of pin-holes dividing the spaces of the dial into a predetermined number of hours, a series of pins for the pin-holes, a stationary ring mounted on the frame back of the spaced disk, a spring-arm attached to the ring on each side of the disk, a contact on each spring-arm located centrally over the disk and arranged for one contact to be engaged successively by the pins on the spaced

disk, a wire leading from each spring-arm to the main circuit, and a main circuit comprising an annunciator, a make-and-break mechanism and a source of electric energy, substantially as described.

8. In an automatic program-clock, the combination of a regulator, a rotatable shaft, a dial on the shaft spaced to designate periods of time, a series of pin-holes dividing the spaces of the dial into other periods of time, a series of pins for the pin-holes for the insertion of a pin in a predetermined hole of the dial, a disk on the shaft provided with a series of notches corresponding to the number of pin-holes of the spaced dial, a compound lever independently mounted on the shaft, an arm connected with the hour-wheel of the regulator and contacting the compound lever at stated periods of time, a pawl engaging the notched disk at predetermined periods of time, a dog engaging a notch of the disk and means actuating the pawl and dog and releasing the notched disk for advancement one notch and movement of the spaced dial forward the distance of a pin-hole, substantially as described.

9. In an automatic program-clock, the combination of a regulator, a rotatable shaft, a spaced divisioned dial, a stationary ring around the dial, a disk on the shaft provided with a desired number of notches, a compound lever independently mounted on the shaft and having a front and rear member, a dog on the front member engaging the notches of the disk, an arm connected with the hour-wheel of the regulator and contacting the rear member of the compound lever at stated intervals of time, a pawl on the stationary ring engaging the notched disk at predetermined times, and a trip striking the pawl and disengaging it from the notched disk, for the advance of the dog to rotate the disk one notch and position the spaced dial thereby, substantially as described.

10. In an automatic program-clock, the combination with a regulator on a series of electric circuits each circuit carrying a number of the annunciators, of a contact-shaft, a train of wheels driving and rotating the contact-shaft, a two-armed contact on the shaft, a series of terminals arranged upon the two-armed contact in the path of travel thereof and successively engaged thereby, and a wire leading from each of the terminals to a main circuit for energizing such circuit, substantially as described.

11. In an automatic program-clock, the combination with a regulator on a series of electric circuits each circuit carrying a number of the annunciators, of a contact-shaft, a driving-train for the shaft consisting of two shafts, a power-spring for each shaft and a driving-wheel for each shaft, a shaft rotated from the driving-wheels, a bearing-wheel on the shaft, a two-armed contact on the contact-shaft, a series of terminals in the path of travel of

the contact-arms, arranged to be successively engaged by the arms and a wire leading from each one of the several terminals to a main circuit for energizing such circuit, substantially as described.

12. In an automatic program-clock, the combination of a shaft having a cam-contact, a gear-wheel on such shaft, a fly or fan operated from the gear-wheel, a notched disk on the contact-shaft, a movable stop-arm engaging the notched disk and a second stop-arm engaging the fly or fan and holding the fly or fan from revolving thereby stopping the operation of the motor, substantially as described.

13. In an automatic program-clock, the combination of a regulator, a main arbor of the regulator, a pin-wheel on the arbor having a series of pins one for every five minutes, a vibrating releasing-lever engaged at its free end by a pin on the wheel, a notched disk, a fly or fan, stop-levers for the notched disk and the fly or fan and a rod connecting the stop-arms and the vibrating releasing-lever, substantially as described.

14. In an automatic program-clock, the combination of a regulator, a main arbor for the regulator, a contact-shaft, a pin-wheel on the main arbor having a series of pins one for every five minutes of time, a vibrating releasing-lever engaged at its free end by a pin on the wheel, a fly or fan, a wheel from which the fly or fan is operated, a pin on such wheel, a stop-arm engaging the pin on the wheel for preventing a complete operation of the motor until the releasing-lever has assumed its normal position and permitting a partial operation of the stop-arm for the notched disk,

a notched disk on the contact-shaft and a motor, substantially as described.

15. In an automatic program-clock, the combination of a regulator having three distinct and separate means for stopping and starting a motor and making and breaking the operations consisting first of a spaced and divisioned dial, contacts coacting with the dial, a two-armed oscillating lever actuated by the dial and stopping the fly or fan of the motor, second, a vibrating lever contacting and stopping the drive-wheel of the fly or fan and actuated from the regulator-clock, and third, a stop-arm engaging the fly or fan and actuated from the movements of the regulator-clock, each mechanism having its own action and all the mechanisms having a conjoined union of action, substantially as described.

16. In an automatic program-clock, the combination of three sets of batteries, three wires leading thereto, a spring-terminal for each wire, a contact-collar on which the terminals bear, a rotating shaft for the contact-collar, an insulated portion on the contact-collar preventing at any one time contact of more than one terminal, a disk or plate on the contact-collar shaft, a series of notches in the periphery of the disk or plate, a compound vibrating lever on the contact-collar shaft and means coacting between the compound lever and the notched disk for giving each set of batteries a period of work and a period of rest and restoration, substantially as described.

ANDREW J. REAMS.
